UNITED STATES PATENT OFFICE.

SAMUEL P. JOHNSON, OF LONGACRE, WEST VIRGINIA.

AUTOMATIC TRAIN-CONTROL SYSTEM.

Application filed April 17, 1922. Serial No. 553,567.

To all whom it may concern:

Be it known that I, SAMUEL P. JOHNSON, a citizen of the United States of America, residing at Longacre, in the county of Fayette and State of West Virginia, have invented certain new and useful Improvements in Automatic Train-Control Systems, of which the following is a specification.

This invention relates to an automatic appliance for stopping railway trains which operates in conjunction with a block signal to prevent the train running into a block when the signal is set to stop it.

More particularly my present invention relates to the novel and effective appliances on the locomotive itself which are controlled by a track trip and when operated serve to close the throttle on a locomotive. My appliance is also designed for a combined electromagnetic and mechanical control of such character that in the event of any defect arising in the electric system, the appliance will act instantly and automatically to close the engine throttle.

The track trip mechanism, which is in part illustrated in my present application, forms the subject matter of an application filed of even date herewith, and is not claimed herein.

My present invention with the above objects in view consists in the novel combination and arrangement of parts which are hereinafter more fully described, illustrated in the accompanying drawings, and more particularly pointed out in the appended claims, it being understood that changes in form, arrangement, and relative position of parts may be made to suit different operating conditions without departing from the essential substance of this invention.

Referring now to the drawings which form a part of this specification:—

Fig. 1 is a side elevation of a conventional locomotive equipped with my present invention, the track trip mechanism being partially illustrated sufficiently to show its co-operation with the locomotive appliances.

Fig. 2 is an enlarged detail view showing the several features of the locomotive appliances detached but connected up.

Fig. 3 is a detail cross-sectional view through the spring motor for operating the valve in the branch pipe from the air brake system which supplies the motor controlling the throttle lever.

Similar reference numerals refer to similar parts throughout the drawings.

As illustrated, 1 is a locomotive engine having any standard type of throttle lever 2 adapted to be set by a latch 3 co-acting with a segment 4. An air cylinder 5 receives waste air through the hose 6^a on branch pipe 6, under control of valve 7, from the train line 8 of the air brake system. The cylinder 5 is mounted in the bracket 9 on trunnions 10 so that it can oscillate vertically about its center, the bracket itself being adapted for lateral adjustment so as to position the cylinder properly for its piston rod 11 to engage the throttle lever 2, this piston carrying a longitudinally slotted yoke 12 in the slot 12^a of which engages a cross pin 13 on the lever. The cylinder, as more clearly illustrated and described in my prior Patent No. 1,345,599, is provided with a piston 14, a stuffing box 15 and an end cap 16 provided with a series of perforations for the escape of air when the piston is moving in the direction of the cap 16.

The yoke 12 carries a cross pin 18 which engages the ratchet latch controlling hand clasp 19 to trip the latch and release the lever, when air enters the cylinder 5 and forces its piston to the right, this release taking place before the play in the slot 12^a has brought the yoke into positive engagement with the throttle lever to close it. The bracket 9 is attached to any suitable part in the cab of the locomotive.

The valve 7 is operated by the mechanism which will now be described and which comprises a cylinder 20 with a spring 21 inside working between the leather piston head 22 and the perforated cylinder head 23^a and tending to force the piston rod 24 to the right. A solenoid 25 has its plunger 26 connected by a rod 27 to one end of a longitudinally slotted link 28, the other end of which is connected to the piston rod 24. A bolt 29 works through this longitudinal slot 100 in the link 28 and through a vertical slot 30 in lever 31 which at an intermediate point is pivoted at 32 in a bracket 33 and which at its lower end carries a segmental gear 34 which meshes with a segmental gear 35 fast on the stem of the valve 7. The cylinder 20 is mounted by brackets 36 under the running board or on any convenient anchorage on the locomotive and in like manner the solenoid is attached to the running board 37 by bolts 110

2
39, or may be otherwise mounted in any convenient manner on the locomotive. The solenoid is connected in a normally closed electric circuit 39 leading from batteries 40 on 5 one side and on the other side being connected by a wire 41 to a switch contact 42 mounted on and suitably insulated from any convenient support on the locomotive, preferably at the rear of its driving wheel. The 10 circuit is normally closed across the terminals 42, 43 by the circuit breaker 44, the current returning over wire 41^a to the battery.

The circuit breaker is in the form of a 15 conducting plate carried by a ratchet wheel 45 rotatable about a pivot 46 and having fast thereon a crank 47. This crank has an elongated slot 48 in its free end which receives a pin 49 by means of which the vertically depending trip rod 50 is pivotally connected thereto, this rod being guided for vertical play between the guide plates 51 mounted on upper and lower upper members 52 and 53 of the rear locomotive frame. At its lower end this rod has an offset 50^a which 20 overhangs the track trip and carries a roller 54 which is adapted to engage the track trip 25 when elevated and to be raised thereby sufficiently to rotate the ratchet wheel 45 about its axis sufficiently and move the circuit 30 brakes to open the circuit at the terminals 42, 43. The trip is operated by a control mechanism in the box 56, which is responsive to an electric make and break switch 57 that is in turn controlled by the 35 position of the semaphore arm 58.

The wheel 45 is provided with a series of ratchet teeth 59 which are engaged by a spring-pressed detent 60 mounted in a U-bracket 61 secured to the frame member 52 and provided with a coil spring 62 surrounding it between the arms of the yoke and pressing a stop collar 63 thereon against the side of the yoke adjacent to the ratchet wheel. The ratchet teeth are disposed so as 45 to be engaged by the detent when the circuit breaker 44 is in "closed circuit" position and are adapted to permit the ratchet wheel to be rotated counter-clockwise. They serve by 50 engaging the detent to prevent the ratchet wheel turning back to close the circuit until 55 the detent is released by the engineer. The solenoid 25 is typical of any electro-magnet which, when its circuit is closed, is adapted to hold the valve in closed position against 60 the action of the spring 21. The cylinder 20 is provided with a valve 64 adapted to throttle the exhaust ports 65 in the right hand cylinder head to regulate the speed of operation of the spring-pressed plunger after the 65 fashion of a dash-pot.

In operation, if the semaphore is set to prevent the train entering a block, the track trip will be raised and an engine approaching the block and not respecting the stop signal will have his engine automatically

stopped in the following manner. The trip 55 will be struck by the roller 54 and, due to its convex surface, will raise the arm 50, rock the ratchet wheel 45 and move the circuit breaker 44 to open the circuit 41, 41^a, 70 the circuit breaker being latched in "open circuit" position by the detent 60. The moment that the circuit is broken to the electro-magnet 25 it is de-energized and the 75 spring 21 at once acts to thrust the piston 22 to the right, carrying with it the arm 31 and, through gears 34 and 35, opening the valve 7. The speed of movement of the piston is controlled by the rate of discharge of air from the right hand end of its cylinder. As 80 the valve 7 opens, the waste escaping through pipes 6 and 6^a enters the left hand end of cylinders 5 and acts on the piston therein to thrust it to the right, this resulting in the cross pin 18 first tripping the ratchet trip and then the yoke engaging the lever pin 19 and drawing the throttle lever to closed position.

As a result, the train is promptly brought 90 to a stop and it cannot be started until the engineer releases the detent 60, whereupon the weight of the arm 50 will act on the released ratchet wheel to swing the circuit breaker 44 into engagement with the contact 42 and 43, whereupon the electro-magnet is 95 again energized and overcomes the tension of the spring 21 and forces the lever 31 to the left, closing the valve 7 and restoring the air brake system to the control of the engineer.

Though I have described with great particularity the details of the embodiment of the invention herein shown, it is not to be construed that I am limited thereto, as changes in arrangement and substitution of equivalents may be made by those skilled in 105 the art without departing from the invention as defined in the appended claims.

Having thus described my invention, what I claim as new and desire to secure by Letters Patent, is:—

1. In an automatic train stop, the combination with an air brake system and a throttle lever having an air motor adapted to close it, of automatic track trip controlled means to close the throttle lever, comprising a branch pipe leading from the brake system to said lever motor, a normally closed valve in said pipe, and an opposed electro-magnet and spring operably connected to the said valve, a circuit comprising a source 115 of current and a circuit breaker, track trip operated means to open said circuit and permit the spring to open said valve and admit air exhausted from the air brake system to operate said motor and close said throttle. 120

2. In an automatic train stop, the combination with an air brake system and a throttle lever having an air motor adapted to close it, of automatic track trip controlled means to draw off air from the drain 125

- pipe and use it to close the throttle lever, comprising a branch pipe leading from the air brake system to said lever motor, a normally closed valve in said pipe, and an opposed electro-magnet and spring operably connected to the said valve, a circuit comprising a source of current and a circuit breaker, said circuit being normally closed and said magnet being adapted to hold said valve normally closed against the resistance of said spring tending to open it, track trip operated means to open said circuit and permit the spring to open said valve and admit air exhausted from the air brake system to operate said motor and close said throttle.
3. In an automatic train stop, the combination with an air brake system and a throttle lever having an air motor adapted to close it, of automatic track trip controlled means to draw off air from the drain pipe and use it to close said throttle lever, comprising a branch pipe leading from the air brake system to said air motor, a valve in said pipe, mechanism to operate said valve, comprising opposed motors, one being an electro-magnet and the other being a cylinder having its piston operable by a coiled compression spring, means to dash-pot the piston's movements in its cylinder, means to normally energize said magnet and thereby hold said valve closed, and trip controlled means comprising a ratchet member, a circuit breaker operable by said member, and a detent to prevent the free return of said ratchet member to initial position after its automatic operation to de-energize said electromagnetic motor.
5. In an automatic train stop, the combination with an air brake system and a throttle lever, of a track trip controlled actuator, a ratchet member operable by said actuator, a circuit closer movable by said member to "open circuit" position when said actuator is operated, a spring-pressed detent adapted to prevent the return of said ratchet member to its initial position, a branch pipe leading from the air brake system, a throttle lever operating cylinder supplied by said branch pipe, a valve normally closing said branch pipe and opposed agencies to control said valve, one being a spring tending to open said valve and the other an electro-magnet tending to hold the valve closed, and an electric supply circuit for said magnet comprising a circuit breaker controlled by said ratchet member.
4. In an automatic train stop, the combination with an air brake system and a throttle lever having an air motor adapted to close it, of automatic track trip controlled means to close said throttle lever, comprising a branch pipe leading from the air brake system to said air motor, a valve in said pipe, mechanism to operate said valve, comprising opposed motors, one being an electro-magnet and the other being a cylinder having its piston operable by a coiled compression spring, means to dash-pot the piston's movements in its cylinder, means to normally energize said magnet and thereby hold said valve closed, and trip controlled means comprising a ratchet member, a circuit breaker operable by said member, and a detent to prevent the free return of said ratchet member to initial position after its automatic operation to de-energize said electromagnetic motor.
5. In an automatic train stop, the combination with an air brake system and a throttle lever, of a track trip controlled actuator, a ratchet member operable by said actuator, a circuit closer movable by said member to "open circuit" position when said actuator is operated, a spring-pressed detent adapted to prevent the return of said ratchet member to its initial position, a branch pipe leading from the air brake system, a throttle lever operating cylinder supplied by said branch pipe, a valve normally closing said branch pipe and opposed agencies to control said valve, one being a spring tending to open said valve and the other an electro-magnet tending to hold the valve closed, and an electric supply circuit for said magnet comprising a circuit breaker controlled by said ratchet member.

In testimony whereof, I, SAMUEL P. JOHNSON, affix my signature.

SAMUEL P. JOHNSON.
